(57) **CLAIM**

The ornamental design for an ornamental cross attachment for footwear, as shown and described.

DESCRIPTION

FIG. 1 is a front view of an ornamental cross attachment for footwear showing my new design.

FIG. 2 is a rear view of the ornamental cross attachment for footwear.

FIG. 3 is a left side view of the ornamental cross attachment for footwear.

FIG. 4 is a right side view of the ornamental cross attachment for footwear.

FIG. 5 is a top view of the ornamental cross attachment for footwear with the bottom view being identical to the top view; and,

FIG. 6 is a perspective view of the ornamental cross attachment for footwear.

The broken line showing of a shoe is for illustrative purposes only and forms no part of the claimed design.
